UNITED STATES PATENT OFFICE.

ALEXANDER A. KLEBERG AND SAMUEL HATT, OF BROOKLYN, NEW YORK.

DESIGN FOR A MONEY-BOX.

SPECIFICATION forming part of Design No. 20,977, dated August 11, 1891.

Application filed May 28, 1891. Serial No. 394,455. Term of patent 3½ years.

To all whom it may concern:

Be it known that we, ALEXANDER A. KLEBERG, a subject of the Czar of Russia, and SAMUEL HATT, a subject of the Queen of Great Britain, residing at Brooklyn, in the county of Kings and State of New York, have invented and produced a new and original Design for a Money-Box, of which the following is a specification, reference being had to the accompanying drawing, in which the figure represents a perspective view of a money-box embodying our new design.

The design consists in a box having the general form of a triangle and having a top 15 in the shape of a three-armed figure. The body A is in general of triangular form, and

the top B is in the form of a three-armed figure. The arms b of said top alternate with openings b', and the outer ends b² of the arms b range laterally at each side of the shank b³. The inner walls of the openings b' are semi-circular, and the lines of the body are continued across the said openings, as at a.

We claim—

The design for a money-box herein shown and described.

ALEXANDER A. KLEBERG.
SAMUEL HATT.
